MECHANICAL MOVEMENT

Herman G. Mueller, Erie, Pa.

Application December 1, 1952, Serial No. 323,478

6 Claims. (Cl. 74—55)

1

This invention relates generally to pumps and more particularly to hydraulic multi-cylinder liquid pumps driven from an external power source and customarily used in lifting the liquid to be pumped, by suction, from a sump and forcing it against hydraulic pressure into a discharge line.

This application is an improvement of my pump disclosed in Patent No. 2,607,296, issued August 19, 1952.

In my said patent, I disclose a pump having two double acting parallel cylinders, each containing a piston. Each piston is actuated by a pair of equal cams mounted on and rotated by a common shaft, the pair of cams for one piston being disposed at an angle of ninety degrees from the pair of cams for the other piston. Each cam operates two followers, one on either side of each cam. The four followers for each pair of cams are mounted on two cross heads disposed between the pair of cams and rigidly tied together with tie rods. The cross head nearest the piston is rigidly secured to the piston rod for actuating its piston.

In the pump disclosed in my said patent, I have disclosed the roller followers mounted on two cross heads rigidly tied together with tie rods. The pistons are at their greatest distance from the center of the cams when they are in the extreme left position and nearest the center of the cams when in extreme right position. On the forward stroke, the right rollers supply the thrust of the piston, discharging the liquid out of the crank end of the cylinder, and these rollers will necessarily be securely in contact with the cams. Due to the tension in the tie rods and cross heads, the left rollers may move out of contact with the cams during this stroke, leaving a small clearance between the cams and rollers. When the cams have rotated one hundred eighty degrees from the extreme left position, the crank end dead center is reached and as the cams move past dead center and begin the return stroke, the thrust from the piston is reversed for discharging the liquid from the head end of the cylinder. This reversal suddenly brings the left rollers in contact with the cams and relieves the stress on the right rollers but, on the return stroke, less clearance between the cams and right rollers results since the tension is relieved in the tie rods.

After the cams have turned one hundred eighty degrees further, bringing the piston back to the extreme left position, the right rollers will again suddenly contact the cams relieving the left roll-

2

ers. Thus, a metallic take-up may occur at each dead center, causing a knock twice per revolution which may damage the cams and rollers.

This knock may be reduced considerably and, 5 in some cases, entirely removed by pre-stressing the tie rods. However, it becomes apparent that with a piston thrust of thirty-two thousand pounds, normal for a seven inch stroke pump, this pre-stress in the tie rods and cross heads 10 will have to be somewhat in excess of thirty-two thousand pounds or about thirty-six thousand pounds, so that on the forward stroke when the tie rods are in tension, the pre-stress is still sufficient to hold the left rollers on the cams. Thus, 15 the load on the right rollers on the forward stroke will be the thirty-two thousand pound thrust of the piston plus the excess of the pre-stress above thirty-two thousand pounds, holding the left rollers on the cams, or a total equal to 20 the pre-stress of thirty-six thousand pounds.

On the return stroke, the left rollers assume 25 the piston thrust and no part of the piston thrust is carried by the tie rods. The total load on the left rollers will be that due to the pre-stress in the tie rods plus the piston thrust, totaling thirty- 30 two thousand pounds plus thirty-six thousand pounds, or sixty-eight thousand pounds. Thus, the load on the left rollers is more than double the piston thrust and will require over-sizing to give the same life as that for the right rollers.

It is, accordingly, an object of this invention 35 to provide a novel cam and follower mechanism in combination with a cam actuated double acting pump.

Another object of the invention is to provide a 40 double acting cam actuated pump in combination with a novel means for eliminating noise and wear in the cam and follower piston drive assembly.

Another object of the invention is to provide a 45 novel spring arrangement to continuously maintain roller followers in contact with a driving cam in a double acting pump.

Another object of the invention is to provide a 50 novel means incorporating a novel fluid pressure device for continuously maintaining the followers in contact with the cam surface in a double acting pump.

Another object is to provide a pump which will 55 be efficient in use and economical to manufacture.

Another object of my invention is to provide a 55 liquid pump capable of high speeds while eliminating the noise and wear usually incidental to such pumps.

With the above and other objects in view, the present invention consists of the combination and arrangement of parts hereinafter more fully described, illustrated in the accompanying drawings, and more particularly pointed out in the appended claims, it being understood that changes may be made in the form, size, proportions, and minor details of construction without departing from the spirit or sacrificing any of the advantages of the invention.

In the drawings:

Fig. 1 is a longitudinal sectional view of a double acting pump incorporating my novel cam arrangement;

Fig. 2 is an enlarged sectional view of the cam assembly shown in Fig. 1; and

Fig. 3 is an enlarged sectional view of another embodiment of the invention showing the cam assembly.

Referring now to the drawings, Figs. 1 and 2 show a crank case 1 mounted on skids 2. Top covers 4 are provided on the crank case 1 for ready access to piston rod packing cases 5 and 6. A main cover 7 is disposed on the top of the crank case 1. The fluid casing 8 is disposed longitudinally of the crank case 1 and has formed therein liquid pumping cylindrical portions 9 connecting closed chambers 10 and 11. Apertures 12 in the casing 8 have seats 13 for seating inverted conical shaped valve heads 15 guided by stems 16. Covers 17 have depending cylindrical portions 18 with coil springs 19 therearound to urge the valve heads 15 into sealing relationship with seats 13. Covers 17 close apertures 20 in the discharge chests 21 in the upper part of casing 8. Discharge outlet 22 leads outwardly from chests 21.

A shaft 29 is journaled in a sleeve 30 and is transversely mounted below the casing 8 and has fixedly mounted thereon two impellers 31, one with right and the other with left hand vanes disposed in annular casings 33 on opposite ends of shaft 29 and to increase the pressure of fluid entering annular casings 33 from the inlet line 35 and passing through to the chambers 10 and 11 through a valved suction passage (not shown).

Crank case 1 has hub member 61. Two pair of eccentric hubs 68, one pair for each piston, are cast integral with hub member 61, one pair being spaced ninety degrees from the other. The throw of each eccentric is preferably made equal to one-half the piston stroke. Around each eccentric is shrunk a hardened and ground cam ring 59.

Engaging each cam ring 59 are two follower roller tires 69 shrunk over and encircling roller bearings 88 mounted on transversely extending shafts 70. One shaft 70 is integral with cross head 72 and the other is integral with cross head 72b. Each pair of main cross heads 72 and 72b are tied together with two main tie rods 56 and two lighter auxiliary tie rods 56b. Main tie rods 56 have nuts 55 at their inner ends with integral heads 55b at the outer end for removal through the opening closed by cover 57. The auxiliary tie rods have nuts 55c at either end for adjusting the tension in helical springs 56d. This tension is adjusted to insure contact of the idling followers on their cams with either stroke of the piston and is constant and independent of the tension in the main tie rods 56 applied during the forward stroke of the piston and relieved during the return stroke.

Guideways 75 and 76 can be adjusted vertically with shims in order to adjust the clearances between the upper guideway 76 and the lower 75 to permit a small relative movement between the

guideway 75 and the tires 69a so that tires 69a can roll on either the upper or the lower guideways 76 or 75 and clear the opposed guideway.

The inner ends of the main tie rods 56 extend through apertures 56f in cross heads 72 and 72b and are secured to third cross heads 72a by nuts 55. Extension rods 58 have tapered ends 58c which are fitted into tapered aperture 58g in cross heads 72a and locked therein by keys 58a. 10 The other ends of the extensions 58 are threaded internally for threadably engaging the threaded ends of piston rods 51 with nuts 81. Splash plates 82 are secured between nuts 81 and cross head extensions 58. The extensions 58 are oil sealed by packing boxes 6. Piston rods 51 have conventional piston heads 83 secured thereto in the cylindrical portions 9 of the casing 8 by the internally threaded end 84 of extensions 85 of the rods 51 serving as a tail rod of the same diameter as the piston rods 51 to equalize the displacements of fluid from either side of the piston heads 83. On either side of the piston heads 83 are mounted conventional rubber packings 86 secured with follower plates 87.

25 The rubber packings 86 ride on hard liners 89 sealed with a conventional rubber gasket 91. The piston rods 51 and the tail rods 85 pass through duplicate stuffing boxes 5 and 92 with conventional duplicate rubber packings 93 and 94 and follower glands 95 and 96. The liners 89 are pressed into the cylindrical portions 9 of the casing 8. It will be evident that the two chambers 10 and 11 are duplicates of each other and have duplicate liners, pistons, rods, and packing boxes 35 for each cylinder.

30 A pulley 100 is mounted on the shaft 63 and rotative force is transferred to the shaft 29 by V-belts. The shaft 63 is driven from a main power source such as a gas engine, diesel engine, steam engine, or electric motor. It will be evident that any form of drive may be used between shaft 63 mounted in the crank case 1 and shaft 29 mounted in the casing 33.

35 In operation, the shaft 63 is rotated by a suitable power source, thereby rotating the pulley 100 mounted thereon to drive the shaft 29 carrying the impellers 31. The rotation of the shaft 63 with cams 59 attached thereto causes the reciprocation of the piston rods 51 and the pistons 83 attached thereto. The discharge valves 15 in the chambers 10 and 11 on each end of the cylindrical portions 9 of the casing 8 open and close in accordance with the pressure variations caused by movement of the pistons 83. The fluid entering 50 chambers 10 and 11 is placed under pressure by the impellers 31 to follow the pistons 83 and to prevent cavitation.

55 On the discharge stroke of the pistons 83, the discharge valves 15 are opened by pressure on 60 their under side from the pistons 83 and the discharge valves then communicate chambers 10 or 11 to the discharge chest 21 which is open to all four discharge valves 15 and leads to the discharge line 22.

65 One embodiment of the improved cam follower arrangement is shown in Fig. 1 with an enlarged view in Fig. 2. At each end of main tie rods 56, steel plates 58b are disposed around tie rods 56 and resilient platens 57a made of rubber or other suitable material are disposed between cross heads 72 and 72b and steel plates 58b. The cross heads 72 and 72b are slidably mounted on tie rods 56 by clearance holes 56f to permit a small relative movement between the

tie rods 56 and cross heads 72 and 72b with changes of tension in the tie rods between the forward and return strokes and to permit alternate compression and expansion of the two rubber platens 51a.

The inner or left ends of tie rods 56 are secured to the third cross head 72a by nuts 55 and this cross head 72a is in turn secured to extension rod 58 which actuates the piston. The auxiliary tie rods 56b are threaded at either end to receive nuts 55c and are also slidably mounted on cross heads 72 and 72b through clearance holes 46a. Helical springs 56d are adjusted for tension with nuts 55c to give a constant load of the followers 69 on the cams 59 during each idle stroke.

Thus, with proper adjustments of nuts 55c to control the compression in springs 56b and with proper adjustment of nuts 55 for pre-stressing the compression in rubber platens 51a, no excessive loads on the working stroke beyond that of the piston thrust is applied and the followers always remain in contact with the cams on the idle stroke.

In the embodiment of the invention shown in Fig. 3, the piston rod 158 is shown connected to the cross head 172a. The only tie rods 156 pass through close fitting holes 159a in cross heads 172a and extend through clearance holes 159b in cross head 172b, through clearance holes 159c in cross head 172c, and through close fitting holes 159e in cross head 172. The inner ends of rods 156 are threaded to receive nuts 155 and have heads 155a at the outer ends thereof. The nuts 155 engage cross heads 172a and the heads 155a engage the cross heads 172. Cylindrical pistons 102 are forged integral with cross heads 172b and extend into close fitting cylinders 105 bored in cross heads 172a. Each piston 102 is fitted with conventional chevron layer or plastic packings 103 and adjustable gland 104 to form an oil type seal between pistons 102 and cylinder bores 105.

Oil feeder holes 106 are drilled through pistons 102 and out one side of cross heads 172b. Oil supply line 107 is connected to holes 106 through check valves 108. One end of line 107 is provided with swivel joints 109 and constant length pipe nipples 110 which contain a constant volume of oil. The oil for the cylinders 102 is supplied by a constant displacement oil pump 111 which is driven by a chain 115 and sprockets 112 from the main shaft 103. A spring loaded oil relief valve 113 is fitted in the pump discharge to maintain a constant pressure of about seventy-five pounds per square inch in the oil supply line 107 and cylinders 105 when the main pump is operated.

Similarly, on the right ends of tie rods 156, cylindrical pistons 102a are forged integral with cross heads 172c extending into cylinders 105a bored in cross heads 172. Similar chevron packings 103a are adjusted by glands 104a forming an oil tight seal between pistons 102a and cylinder bores 105a. Similarly, oil feeder holes 106a pass through pistons 102a and out the side of cross heads 172c and are supplied with oil through check valves 108a from oil line 107.

When the main piston is being drawn forward toward the center of the cams 59, the load will be applied to followers 69a moving piston 102a approximately ten-thousandths of an inch into cylinder 105a until check valve 108a closes. After check valve 108a closes, the oil in cylinder 105a will be compressed until the pressure acting on

the piston area equals or slightly exceeds the piston thrust. This thrust will be transmitted by tension in tie rods 156 to cross head 172a and in turn by tension in extension 158 to the piston, leaving cross head 172b unloaded. Since at this point oil pressure in oil line 107 is increased and is decreased in hole 106, check valve 108 will open, exerting a small pressure on piston 102 which multiplied by the area of piston 102 is the load applied to idling follower 169 at this point of the stroke and which insures its contact with the cam.

When the crank end of the stroke is reached and the piston is reversed, the load will be applied to follower 169, moving oil piston 102 into cylinder 105 until check valve 108 closes, thereby building up the oil pressure in cylinder 105 to the amount needed to actuate the piston through cross head 172a. Simultaneously, cross head 172c and follower 169a will be unloaded and oil will enter from oil line 107 through check valve 108a, exerting this small pressure on piston 102a to maintain follower 169a in contact with cam 59 during its idle stroke. The pressure in line 107 is adjustable by relief valve 113 so the follower load on the idle stroke is readily adjustable.

Thus, the reversals of the cylinders at dead center are eased, the rollers always remain in contact with the cams, the roller maximum load is only a small adjustable amount in excess of the piston thrusts, and all metallic shocks are eliminated, insuring a quietly operating pump and no brinelling of the rollers on the cams.

In my improved pump with the pistons operated by properly designed cams, much higher speeds are permitted, giving not only a constant flow without pulsations but also easing valve impacts and all knock between cams and followers are entirely eliminated.

In the foregoing specification, I have set forth the invention in its preferred practical forms but I am aware that the structure shown is capable of modifications within a range of equivalents without departing from the invention which is to be understood is broadly novel as is commensurate with the appended claims.

What I claim is:

1. A shaft oscillating mechanism comprising a shaft, a first cross head attached to said shaft and movable therewith, a second cross head, tie rods extending through said cross heads, a first auxiliary cross head associated with the first cross head and a second auxiliary cross head associated with the second cross head, a follower on each auxiliary cross head, a cam engaging the followers, and means disposed between each of said first cross head and said first auxiliary cross head and between said second cross head and said second auxiliary cross head to apply a pressure therebetween, said means comprising an oil cylinder on one cross head and a piston operable therein, and means to supply oil under pressure to said cylinder.

2. A shaft oscillating mechanism comprising a shaft, a first cross head attached to said shaft and movable therewith, a second cross head, tie rods extending through said cross head, a first auxiliary cross head associated with the first cross head and a second auxiliary cross head associated with the second cross head, a follower on each auxiliary cross head, a cam engaging the followers, and means disposed between each of said cross heads and each auxiliary cross head to apply a pressure therebetween, said means disposed between said cross heads comprising a

cylinder on one cross head and a piston operably associated with the cylinder, a piston in the cylinder engaging the auxiliary cross head, means to supply oil to said cylinder, and a check valve between said oil supply means and said cylinder.

3. The mechanism recited in claim 2 wherein the means to supply oil to the cylinder comprises a pressure regulated oil supply means, a bifurcated pipe line having a branch to each cylinder conducting oil from the supply to each of said cylinders, and a check valve in each branch of the line whereby oil is allowed to flow from said supply to said cylinders and the flow of oil from said cylinders is opposed by said check valves.

4. A shaft oscillating mechanism comprising a shaft, a first cross head attached to said shaft and movable therewith, a second cross head, tie rods extending through said cross head, a first auxiliary cross head associated with the first cross head and a second auxiliary cross head associated with the second cross head, a follower on said auxiliary cross heads, a cam engaging the followers, and means disposed between each of said cross heads and each auxiliary cross head to apply a pressure therebetween, said means disposed between said cross heads comprising a cylinder on the cross head and a piston operably associated therewith on the auxiliary cross head, means to supply oil to said cylinder, a check valve between said oil supply means and said cylinder, and a pressure regulating means between said oil supply source and said cylinder.

5. A shaft oscillating mechanism comprising a shaft, a first cross head attached to said shaft and movable therewith, a second cross head, tie rods extending through said cross head, a first auxiliary cross head associated with the first cross head and a second auxiliary cross head associated

5 with the second cross head, a follower on each auxiliary cross head, a cam engaging the followers, and means disposed between each of said cross heads and each auxiliary cross head to apply a pressure therebetween, said means disposed between said cross heads comprising a cylinder on the cross head and a piston operably associated therewith on the auxiliary cross head, means to supply oil to said cylinder, and a check valve between said oil supply means and said cylinder, said pressure source being attached to a fixed part of the machine.

6. A mechanism comprising cams, means to rotate the cams, two followers disposed on opposite sides of said cams, cross heads attached to said cams, tie rods extending through said cross heads, a resilient platen disposed on each of said cross heads, means on each tie rod engaging one resilient platen and means on the tie rod engaging the other resilient platen and an end of said tie rod opposite said one platen connecting said tie rods, a shaft, auxiliary tie rods connecting said cross heads, and resilient means on said auxiliary tie rods urging said cross heads toward each other.
